CLUTCH MECHANISM

Filed Sept. 3, 1930

UNITED STATES PATENT OFFICE

JOHN R. ATKINSON AND ROBERT GOODELL, OF LOS ANGELES, AND JOHN K. STEGE, OF HUNTINGTON PARK, CALIFORNIA; SAID GOODELL AND STEGE ASSIGNORS TO SAID ATKINSON

CLUTCH MECHANISM

Application filed September 3, 1930. Serial No. 479,443.

Our invention relates to new and useful improvements in clutch mechanisms and especially to an automatic intermittent key actuated device, wherein the important object is to produce an improved instantaneous gripping and holding action between the line drive and the power producing the work, and an instantaneous automatic releasing of the parts as soon as the work is completed in combination with improved means in general for aiding in accomplishing the foregoing.

The device is particularly adapted for use on machines for making stereotype plates for printing for the blind, the improved application of which invention is copending, and for this reason since the action of a machine of this character is similar to the action of a typewriter it is obvious the short intervals of time occurring between the successive steps of the work must be met, and accomplished with a combined quick power retarding and accelerating control.

In the Braille method of printing or writing for the blind the letters are raised above the surface and all the letters occurring in the alphabet are composed of different combinations of styli arranged in cells consisting of six styli in all. There are six keys which operate the styli singly or plurally which comprise the various letters.

These styli are assembled in a stylus block, and the styli are movable vertically therein by means of reciprocating cam rods, there being a separate rod for each stylus. These rods are each in turn actuated by an operating key or keys. Therefore, by depressing one or more keys the corresponding stylus is elevated and held in raised position in the stylus block so long as the operating key remains down. The stylus block is actuated by an eccentric which is under direct control of the clutch mechanism operable thru the medium of each operating key or combination of keys.

The eccentric will also continue to operate the styli in the stylus block as long as an operating key remains down, and at each revolution of the eccentric the stylus block is raised to bring the elevated stylus in communication with a cooperating matrix hav-

ing at its lower end, means adapted to receive the upper ends of said styli.

In the accompanying drawings are shown five figures, of which:

Fig. 1 is a perspective view illustrating an embodiment of the invention as applied to a Braille press, only sufficient parts of the press being shown to identify the invention therewith;

Fig. 2 is a section taken on the line 2—2 of Fig. 1;

Fig. 3 is a perspective view of the rocker dog and rocker pin which actuates the cam sleeve;

Fig. 4 is a section taken on the line 4—4 of Fig. 3; and

Fig. 5 is a detail broken away view showing the relation of the rocker pin to the cam sleeve and ball cage on a larger scale.

The complete assembly of the clutch mechanism with the Braille press may be seen by referring to our copending application, the title of which is Improved machine for making stereotype plates for printing for the blind, Serial No. 479,444, filed September 3, 1930.

The foregoing description which is taken in conjunction therewith though not shown here, will suffice to link the present invention with its parent invention.

The numeral 1 designates a portion of an adjustable connecting rod which is actuated by the operating key not shown but hereinbefore referred to, said key having a three-fold function. It operates the escapement to move selectively one space at a time; it operates its corresponding stylus; and it, thru mechanism now to be described, operates to free the rocker dog which under the control of a compression spring causes a partial rotation of the rocker pin which shifts the ball cage in a clockwise direction and the cam sleeve in a counter-clockwise direction, to effect through the medium of the balls a clutching action whereby to rotate the eccentric and rod carrying the stylus block with the styli therein and complete the cycle of operation.

The numeral 2 designates a portion of the connecting rod which carries the stylus block

wherein the different styli are selectively elevated and this, together with the reference to the adjustable connecting rod 1 aforesaid will sufficiently link the clutch mechanism with that portion of the parent invention, which will clearly portray its function and the purpose for which it is intended.

Referring specifically to Fig. 1 we show a clutch mechanism the supporting arms 3 and 10 3a of which are shown broken apart from their main frame. Into the extremities of said arms is journaled a shaft 4, and upon said shaft through the medium of said cam sleeve and ball cage is ball-bearingly mounted a pulley 5 driven by a belt 6. The clutch mechanism is mounted on the shaft 4 adjacent the pulley 5 and is adapted to be thrown into and out of engagement with said pulley at will.

20 There is an eccentric mounted on said shaft to travel rotatively therewith to operate the connecting rod which carries the stylus block. It will be seen that the eccentric 28 has a sleeve portion which comprises 25 an inner shank member 29, an enlarged portion 8, and a terminal portion 8a, all these parts constituting a unit, which, by means of the pin 42, is secured to the shaft 4 to rotate therewith.

30 The eccentric is pinned to the shaft on which it is mounted so that said shaft may have a brake applied thereto to make more sensitive the action of the clutch mechanism.

35 The clutch mechanism proper comprises a rocker dog 7, Figs. 1 and 3, slightly rotatably and rotatively carried in a recess in the enlarged member 8, the round portions 9 and 10 of the rocker pin 11 being journaled in the sides 12 and 13 of the member 40 8 in which the recess is formed. The rocker pin is fixedly held to the rocker dog by a key pin 14.

45 The extension 11 of the rocker pin extends into hub portion 15 of the pulley 5 so as to terminate just slightly in advance of the face of the pulley. The pulley 5 normally idles on the balls 22 in the ball cage 21.

50 The rocker pin extension 11 is anticlastic it having two concave and two convex surfaces, 16 and 17 respectively. The convex surfaces are adapted to be seated in splines 18 and 19, the spline 18 being located in the cam sleeve 20 and the spline 19 being located in the ball cage 21. The edges of the spline 18 are 55 rounded at 18a and 18b, see Fig. 5, to conform with the concavities 16 of the rocker pin extension. The cam sleeve 20 is loosely mounted upon the extension 8a of the eccentric, and rotates therewith by virtue of the extension 60 11. It is also slightly reversibly shiftable thereon. (See full and dotted line positions in Fig. 2.) There are a plurality of cam elements 27 having inclined faces, and there is a root 23 formed by each of the cam elements 65 with the outer surfaces of said sleeve. Over

said cam sleeve and inside the bushing of said hub is a ball guide or cage 21. The ball cage has a slight clearance at both ends so that it may be reciprocated longitudinally of the shaft axis.

70 Within the ball cage 21 is housed the balls 22. These balls are adapted to creep up the inclines of the cam elements 27 of the cam sleeve as soon as the dog under the action of the spring 24 has rotated the rocker pin extension 11 on its axis so as to recede the cam sleeve and cause a slight advancement of the ball cage.

75 The centrifugal force of the balls and the ball cage when they are temporarily unconstrained after the movement of the rocker pin and after the reverse shifting of the cam sleeve has been effected, are advanced and the balls are thrown into tight gripping relation between the inclined faces of the cam elements of the sleeve and the inner periphery of the hardened insert 26 in the hub of the pulley.

80 The balls 22 normally playing between the hard steel bushing 26 seated in the hub of the pulley 5 and in the roots 27 of the cam elements of the sleeve 20 upon being advanced by the foregoing operation are not only caused to creep up the inclined faces of the cam elements by the reverse shifting produced by rotating the rocker pin but the centrifugal force expands the orbital path of the balls in which they are travelling tightly gripping the cam sleeve in interlocking relation with the hub of the pulley, thus causing the two to rotate in unison. The clutching action of the balls against the inner periphery of the steel bushing 26 by virtue of their advancement up the inclined faces of the cam elements thru the latter operation 90 in turn causes the member 8 to rotate and it being connected to the eccentric 28 thru the medium of the shank 29 effects rotation of said eccentric.

95 The arm 3 supports a pair of laterally extended bearing supports 30 and 31 into which is journaled a stub shaft 32. On one end of the stub shaft is fastened a rocker lever 33. The rocker lever has two oscillative ends; one is connected to the adjustable connecting rod 1 actuatable by the operating key, and the other end is connected to a tensioned spring 34.

100 Intermediate of the bearing supports 30 and 31 is pinned to the shaft 32 a yoke 35, and whenever said rod 1 is elevated the yoke 35 is rocked to the position indicated in dotted lines, which allows the rocker dog 7 under the action of the spring 24 to rock the rocker pin extension 11, thereby permitting the balls to be advanced into locked engagement with the faces of the cam sleeve and the bushing in the hub of the pulley, whereupon 105 said member 8 is turned and with each rotation thereof the eccentric 28 elevates the rod 110 120 125 130

2, thus lifting the stylus block as afore described.

Rearward of the spring 24 is a screw adjustment 24a, which may be utilized to take up the wear on the spring 24 thereby governing its tension. The screw adjustment also provides means whereby a new spring may be inserted without dismantling the mechanism.

- 10 The manual depressing of each operating key or keys throws the yoke 35 provided with a cam face 35a to dotted position which allows the spring 24 to produce a slight rotation of the dog 7 whereby to rotate the rocker pin and also produce a slight reverse shifting of the cam sleeve and the ball cage. When the operating key is released the yoke under the action of the spring 34 returns it to the full line position.
- 15 Normally the dog 7 is in contact with the yoke 35 in the full line position and the pulley 5 is free wheeling on the balls 22 which at that time are positioned in the roots 27 of the cam elements altho they extend sufficiently beyond the periphery of the ball cage for the pulley to idle upon.

20 When the operator depress a key the yoke 35 is shifted to dotted position at which time the dog 7 under the action of the spring 24 is slightly rotated whereby to rock the rocker pin extension, reversely shift the cam sleeve and advance the ball cage so as to produce a clutching action between the hub of the pulley and the inclined surfaces of the cam elements. Then the eccentric is operated to perform its function and so long as the key is held down by the operator this performance would be carried on indefinitely. However, as previously pointed out, the operator synchronizes her movement with that of the machine so that usually when the eccentric is down the yoke 35 is in, or in other words is assuming, the full line position.

25 It will therefore be obvious that when the operator has released the key the yoke is in full line position and the dog is travelling in the full line position coming up to lock in engagement with the yoke whereby to re-shift the rocker pin and idle the pulley as the eccentric is travelling in the down position.

30 Therefore to gradually feed the dog 7 into engagement with the yoke 35 a portion of the yoke is rounded at 35b. By virtue of this rounded portion and the special configuration of the curved surface of the dog the dog will always be fed easily into tight gripping relation with the cam face of the yoke. The cam face of the yoke diminishes 35 in relative relation with respect to the increased curvature of the dog as the dog traverses thereunder, during which interval of time the rotation of the dog also takes place until the dog is locked to the yoke, by which movement of the dog the rocker

pin extension shifts the ball cage counter-clockwise and the cam sleeve clock-wise positioning the balls in the roots of the cam elements, thus freeing the contact of the balls between the inclined surfaces of the cam and inner periphery of the hub bushing thereby permitting the pulley hub to rotate on the roller bearings of the ball cage.

35 Although the depressing of the key is timed by the operator so that the dog will engage with the end of the yoke 32b as it comes up, to provide for any side travel of the yoke over the dog when the dog is along side the yoke as it is assuming full line position, we have rounded off the corresponding engaging edges 7a of the dog and 35c of the yoke so that the yoke will always slip over the dog in any position it engages it.

40 With each depression of the operating key which also depresses the spacer bar, said rod 1 is elevated and said clutch is operated which operates the eccentric, the rod 2 and the stylus block (not shown) thereon.

45 The arm 3 is provided with a flange 36, a portion of which is developed into a lug 37, which lug is adapted for having fastened thereto a brake band 38 surmounting a brake drum 39 fastened to the shaft 4 by a pin 40.

50 The shaft 4 is extended beyond its bearing on the arm 3 sufficiently to accommodate the mounting of the brake drum. The brake band is adjustable to different degrees of tightness through the agency of the brake adjustment 41.

55 In order that a retardment may be given to the travel of the eccentric by the use of the brake disc 39 the shaft 4 is pinned to the shank 29 by a pin 42 to accomplish the latter purpose.

60 Referring again to the clinching action of the balls, cam sleeve and pulley; normally in inoperative position the bushing 26 keyed to the pulley hub is rotating freely or idling about the balls 22, ball cage 21, and cam sleeve 20. When the key extension 11 of the rocker pin is operated to cause the ball cage to advance clock-wise and shift the cam sleeve counter-clockwise the balls will advance up the faces of the cams and assume a pinching relation between them and the bushing 26, thus causing a clutching or gripping action, so that all the parts correlated rotate in unison. At the beginning of this pinching action of the said balls 115 with relation to the parts adjacent to them, the ball cage 21 is stationary, and in other words the inertia resistance required to start said ball cage to rotating in the clock-wise direction causes said balls to wedge 120 more firmly into the clutching position.

65 It will be obvious that at certain speeds the centrifugal action of the balls alone, due to the fact they are always rotating, on account of the pulley idling thereon, would 125

be sufficient to advance the ball cage after it was temporarily unconstrained by the rocking of the rocker pin after it had shifted the cam sleeve. However, the curved portion of the rocker pin extension is made to bear upon the sides of the spline 19 in the ball cage to make this action always positive.

Claims.

1. In a device of the character described, a shaft, a pulley ball bearingly mounted to normally idle on said shaft, a hub for said pulley, a bushing within said hub fixed thereto, an eccentric mounted on said shaft, said eccentric having an extension which extends into said hub and bushing, a cam sleeve loosely mounted on said extension to rotate therewith, a ball cage between said cam sleeve and bushing, a series of balls in said cage, and means to produce a relative circumferential movement between said ball cage and cam sleeve to intermittently cause a clutching action to take place. 70
2. In a device of the character described, a shaft, a pulley ball bearingly mounted to normally idle on said shaft, a hub for said pulley, a bushing within said hub fixed thereto, an eccentric mounted on said shaft, said eccentric having an extension which extends into said hub and bushing, a cam sleeve provided with cam elements loosely mounted on said extension to rotate therewith, a ball cage between said cam sleeve and bushing, a series of balls in said cage adapted to be shifted on the face of said cam element to and from positions wherein they perform a clutching action, and means to produce a relative circumferential movement between said ball cage and cam sleeve to intermittently cause a shifting of said balls whereby an initial gripping and final clutching action takes place. 75
3. In a device of the character described, a shaft, a pulley adapted normally to idle on said shaft, a hub for said pulley, a bushing within said hub and fixed thereto, an eccentric mounted on said shaft, said eccentric having an annular extension which projects into said hub and bushing, a cam sleeve loosely mounted upon said extension to rotate therewith, a ball cage between said cam sleeve and bushing, a series of balls in said cage, there being cooperating keyways, one of which is located in said cam sleeve and the other in said ball cage, and a rockable key to cause a relative circumferential movement between said ball cage and cam sleeve, one side of said key engaging one of said keyways and the other side of said key engaging the other of said keyways. 80
4. In a device of the character described, a shaft, a rotary member ball bearingly mounted normally to freely turn on said shaft, a hub for said rotary member, an eccentric mounted on said shaft, said eccentric having an annular extension which projects
5. In a device of the character described, a shaft, a rotary member adapted normally to idle on said shaft, a hub for said rotary member, an eccentric mounted on said shaft, said eccentric having an annular extension which projects into said hub, a cam sleeve loosely mounted upon said extension to rotate therewith and partially rotate thereon, a ball cage between said cam sleeve and the interior of said hub, a series of balls in said cage, said balls being adapted to perform a clutching action between the cam elements of said sleeve and the interior of said hub, and means to cause a relative rocking movement between said ball cage and cam sleeve to produce and discontinue such clutching action, the last recited means comprising a key operatively related to said ball cage and cam sleeve, a dog fixed to said key, a spring normally holding said dog in an extended position, and a cam element movable to and from a position wherein it is engaged by said dog to retract the latter against the opposition of said spring at each rotation of said shaft. 90
6. In a device of the character described, intermittent clutching means, comprising a normally non-rotating shaft, a continuously rotating member mounted on said shaft, there being an annular space between said shaft and a portion of said member, a cam sleeve in said space having inclined sides, a ball cage in said space, balls in said cage adapted to be moved up said inclined sides to perform a clutching action and means to vary the orbital path in which said balls are travelling from an inoperative clutching position to an operative clutching position and vice versa whereby to produce and discontinue said clutching action, the inoperative clutching position of said balls providing a roller bearing for the continuously rotating member to idle upon. 95
7. In a device of the character described, intermittent gripping means comprising a normally non-rotating shaft, a continuously rotating member mounted on said shaft, there being an annular space between said shaft and a portion of said member, a cam sleeve in said space having cam elements, a ball cage in said space, the balls of which are adapted to move from a position wherein they perform a rolling action for said continuously rotating member to idle upon to a position 100
8. In a device of the character described, a shaft, a rotary member ball bearingly mounted normally to freely turn on said shaft, a hub for said rotary member, an eccentric mounted on said shaft, said eccentric having an annular extension which projects

wherein they perform a gripping action between the inclined sides of the cam element and said continuously rotating member, and means to cause a rocking movement of each of said ball cage and said cam sleeve to accomplish such actions.

8. In a device of the character described, intermittent clutching means comprising a normally non-rotating shaft, a continuously 10 rotating member mounted on said shaft, there being an annular space between said shaft and a portion of said member, a cam sleeve in said space, a ball cage in said space, balls in said ball cage, and means to cause a relative 15 rocking movement between said ball cage and cam sleeve in order to move said balls to and from positions wherein they perform a clutching action between the inclined sides of the cam elements of said cam sleeve and said 20 continuously rotating member, the last recited means including a key interengaging between said ball cage and said cam sleeve, and means to operate said key.
